UNITED STATES PATENT OFFICE

FORREST A. HEATH, OF JERSEY CITY, NEW JERSEY.

MIXING DEVICE FOR FLUIDS.

1,165,875.

Specification of Letters Patent. Patented Dec. 28, 1915.

Application filed November 20, 1912. Serial No. 732,493.

To all whom it may concern:

Be it known that I, FORREST A. HEATH, a citizen of the United States, and resident of Jersey City, in the county of Hudson and State of New Jersey, have invented certain new and useful Improvements in Mixing Devices for Fluids, of which the following is a specification.

This invention relates to certain improvements in means for rendering more uniform and homogeneous mixtures of gases and more particularly the mixtures of air and liquid fuel for use in internal combustion engines.

The invention involves certain improvements over the construction disclosed in the patent to Morse, No. 1,110,223, granted September 8, 1914, the object being to simplify the construction, reduce the cost of manufacture, and better adapt the device for use in connection with piping already installed as the intake of an engine or as other mixture-delivering conduit. The basic principle involved in this construction and that set forth in the patent above referred to involves the swirling of the mixture as it passes through the conduit and causing the swirling gas to impinge upon interfering elements which serve to break up the minute drops or globules of liquid carried along with the gas and to render the mixture as uniform and homogeneous as possible. This is accomplished by means of a fixed blade or rib obliquely arranged in the conduit preferably in the form of a helix projecting a short distance from the inner wall thereof and disposed adjacent to a series of interfering elements preferably in the form of a coarse wire mesh. The helical deflector does not materially reduce the cross sectional area of the conduit but causes the gas to swirl in a spiral or helical path about the axis of the conduit even when the engine is being operated at low speeds and the velocity of the gas is slow. At high speeds and velocities it is still effective in producing the swirl but being of small area as compared with the total area of the passage, it does not materially interfere with the free passage of the mixture. The interfering elements are relatively widely spaced but being at an angle to the path of the impinging mixture are struck by a large portion of the minute drops or globules of fluid and also sets up eddies or currents in the mixture which cause the com-

plete vaporization of any drops or globules which may have escaped impinging upon interfering elements.

A deflector in the form of an oblique or helical blade or rib may be formed within the manifold pipe integral therewith, and the pipe if cast may have the ends of the interfering elements embedded therein or may serve to support the interfering elements independently of the baffle. In a preferred construction which is adapted for use in connection with manifolds or intake pipes already in use, the helical deflector and the interfering elements are carried by and rigidly secured to a sleeve adapted to be slipped inside of the manifold or intake pipe and held in place in any suitable manner. This permits the installation of the device by a mere separation of two sections of the manifold or intake pipe, the placing of the sleeve therein and the bolting together of said sections without any readjustment or re-arrangement of the parts. One simple means of holding the sleeve in place involves a terminal flange on the latter which may be clamped between abutting ends of the pipe or conduit within which the device is placed.

Reference is to be had to the accompanying drawings forming a part of this specification in which similar characters of reference indicate corresponding parts in all the views, and in which—

Figure 1 is a side elevation of a portion of a two-cylinder engine, a portion of the intake pipe being shown in section with my improved device therein; Fig. 2 is an end view of the device *per se*; Fig. 3 is a longitudinal section through said device; Fig. 4 is a section in perspective of one-half of the sleeve prior to the attaching of the interfering elements, and Fig. 5 is a longitudinal section through a portion of a cast metal conduit having the helically disposed deflector forming a permanent part thereof.

One form which my invention may assume is that disclosed in Figs. 1 to 4, inclusive, in which there is employed a sleeve 10 of very thin metal and of such diameter as to closely fit within the conduit or intake pipe in connection with which the same is to be employed. This sleeve preferably has an outwardly-extending flange 11 at one end thereof and which may be clamped between abutting ends of pipe sections as indicated in Fig. 1, so as to permanently position the

sleeve. It is of course evident that any other suitable means may be employed for insuring this positioning, but the flange is a very simple and convenient means to this end, as it requires no change in the construction of the pipe and if the device be removed after having been installed, the pipe remains in its original condition. The sleeve itself may be drawn up from a flat blank of which the flange forms the peripheral portion, or the sleeve may be a section of tubing with the flange expanded or spun out at one end, or the flange may be formed from a separate piece of metal soldered or otherwise secured to the sleeve.

Within the sleeve is a deflector 12 of a width preferably less than the radius of the sleeve and arranged so as to constitute a section of a spiral convolute. The deflector is of such length that it extends only part way around the peripheral wall of the sleeve and is illustrated as being of greater width at the upper or outlet end of the sleeve than at the inlet end. This variation in width is not essential although it facilitates the giving of the desired swirl to the gas with the minimum retarding effect on the latter. The deflector is preferably formed of a piece of sheet metal and may be secured in place in any suitable manner, as, for instance, by soldering.

Adjacent to the outlet or delivery end from the deflector, I interpose a series of interfering elements which preferably lie in a plane at right angles to the axis of the sleeve, although a variation in this angle is permissible. The interfering elements are illustrated as a series of wires 13, interwoven to form a very coarse wire mesh lying in a plane at an acute angle to the swirling direction taken by the gas as it leaves the end of the baffle. The acuteness of this angle may be varied by tilting the plane of the interfering elements in respect to the axis of the device but when arranged at right angles to said axis and with the deflector of the pitch illustrated, I am able to secure very efficient results. The volume of the gas to be passed, the speed of the swirl, and the resistance offered by the interfering elements, should be related to each other, and this is controlled by the diameter and cross sectional area of the conduit as compared with the width and area and the pitch of the deflector and also by the number and size of the interfering elements. The area of the deflector should be less and preferably much less than half of the area of the conduit and the obliquity of the deflector should be about that shown in the drawing, that is, at an angle of 45° or less to the axis of the conduit. This gives a very effective swirl to the mixture at low velocities and at the same time avoids any choking effect at the maximum velocity.

The use of such relatively small area deflector to excite rather than to compel the whirl at all speeds without choking effect at the higher speeds, I believe to be a very important feature of my present invention.

The interfering elements are, as previously stated, preferably in the form of a coarse wire screen, and this screen may be secured in place in any suitable manner. A simple and convenient means of securing the screen is that illustrated in the accompanying drawings in which the outer end of the sleeve is provided with an inwardly-projecting bead 14 presenting a shoulder adjacent to the open end of the sleeve and upon which the screen may rest. The terminal portion of the sleeve may be beaded or spun inwardly to form a flange firmly holding the screen against the shoulder and permanently retaining it in place.

As I have previously indicated, the particular means illustrated in Figs. 2, 3, and 4 for securing the spiral convolute and interfering elements in place, is not essential to my invention as they may be secured in various other ways.

In Fig. 5, I have illustrated a section of a cast metal pipe 16, which may constitute a portion of the inlet to the engine, a portion of the manifold or a portion of any pipe through which it is desired to deliver a gaseous mixture. In this specific construction, the interfering elements may be embedded in a core with their ends projecting so that said ends will be cast into the wall of the pipe and the screen permanently held in position. The section of spiral convolute 12^a may also be retained in place in the same manner or may form an integral portion of the casting itself.

Having thus described my invention, what I claim as new and desire to protect by Letters-Patent is:

1. In a hydrocarbon vaporizing device for explosive engines, a conduit having an approximately straight axis, and a stationary, obliquely disposed, deflecting blade or rib rigidly secured to and projecting inwardly from the inner peripheral wall of the conduit, the deflecting surface being of an area materially less than half the cross section of said conduit, in combination with a plurality of stationary, open spaced interfering elements extending transversely of said conduit and having their aggregate obstruction area small as compared with the cross section of said conduit and rigidly secured thereto closely adjacent to said deflecting means.

2. In a hydrocarbon vaporizing device for explosive engines, a conduit having an approximately straight axis, and provided with a stationary, obliquely disposed, deflecting blade or rib projecting inwardly from the inner peripheral wall of the con-

duit, the total projected or obstructive area of deflecting surface being materially less than half the cross section of said conduit, in combination with a plurality of stationary, transversely arranged, open spaced interfering elements located adjacent the delivery end of said deflecting means and having their aggregate obstruction area small as compared with the cross section of said conduit.

3. An engine inlet pipe and a stationary sleeve removably disposed therein and telescoping therewith and having a helically disposed deflecting blade or rib having an area much less than the cross sectional area of said sleeve rigidly secured to and projecting inwardly from the inner peripheral wall thereof, in combination with a plurality of stationary, widely-spaced, small-area, interfering elements arranged transversely of said sleeve adjacent the delivery end of said deflector.

4. A device of the class described, comprising a thin metal sleeve adapted to telescope within an engine inlet pipe and having one end thereof provided with a positioning and retaining flange, a coarse wire screen secured at the opposite end of said sleeve, and a helically-disposed deflector secured to the inner surface of the wall of said sleeve and extending from adjacent one end to adjacent the

opposite end and being of materially less width than the radius of said sleeve and being of gradually increasing width from the end adjacent said flange to the end adjacent said screen.

5. A device of the class described, comprising a thin metal sleeve, a coarse wire screen secured at one end of said sleeve, and a helically-disposed deflector secured to the inner surface of the wall of said sleeve and extending from adjacent one end to adjacent the opposite end and being of materially less width than the radius of said sleeve and being of gradually increasing width from the end adjacent said flange to the end adjacent said screen.

6. A device of the class described, comprising a thin metal sleeve, a coarse wire screen secured at one end of said sleeve, and a helically-disposed deflector secured to the inner surface of the wall of said sleeve and extending from adjacent one end to adjacent the opposite end and being of materially less width than the radius of said sleeve.

Signed at New York city, in the county of New York and State of New York, this 19th day of November, A. D. 1912.

FORREST A. HEATH.
